UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

BANK.

1,294,810.

Specification of Letters Patent. Patented Feb. 18, 1919.

Application filed February 18, 1918. Serial No. 217,928.

To all whom it may concern:

Be it known that I, JOSEPH KOMOROUS, a citizen of the United States, residing at Chicago, in the county of Cook and State of Illinois, have invented a new and useful Improvement in Banks, of which the following is a specification.

My invention relates, more particularly, to improvements in savings banks of the small, portable type and preferably adapted to be carried about in a person's pocket and into which coins may be readily inserted, and be withdrawable therefrom only upon opening the bank through the medium of a tool especially designed for this purpose, this type of bank being commonly employed at savings-bank institutions for distribution among its customers.

My primary object is to provide a novel and simple construction of bank structure of the general type above referred to, the parts of which may be readily assembled to close the bank for the reception of coins, and may be readily disassembled by the use of the proper tool, but present relatively great difficulty to opening the same by any means other than a particular tool provided for this purpose; and other objects as will be manifest from the following description.

Referring to the accompanying drawings:—

Figure 1 is an edge view of a construction of bank in accordance with my invention. Fig. 2 is a bottom plan view of the cover of the bank. Fig. 3 is a plan view of the body of the bank with the cover removed. Fig. 4 is a broken plan section of the bank showing the tool for operating the locking mechanism, in place. Fig. 5 is a broken developed view of the inner surface of the circular side-wall thereof adjacent the coin-slot. Fig. 6 is a broken transverse section through the bank. Fig. 7 is a section taken at the line 7 on Fig. 3 and viewed in the direction of the arrow. Fig. 8 is an edge view of another form of bank in which my invention is embodied. Fig. 9 is a plan view of the body of the bank of Fig. 8 with the cover removed. Fig. 10 is a bottom plan view of the cover of this bank. Fig. 11 is an enlarged section taken at the line 11—11 on Fig. 8 and viewed in the direction of the arrows. Fig. 12 is a broken, plan, sectional, view of the bank taken at the line corresponding with the line 11—11 in Fig. 8, but viewed in the

direction opposite to the arrows in this figure, the spring locking mechanism which is shown as moved to releasing position by a tool inserted into the bank, being shown in full plan, and the shoulders on the cover section coöperating with the locking means being shown by dotted lines; and Fig. 13 a view in elevation of the spring locking mechanism and the coin-check mechanism for the slot of this bank, these parts being shown disassembled from the other parts of the bank.

Referring to the construction illustrated in Figs. 1 to 7 inclusive, the bank, generally stated, which in the construction shown is circular, consists of a body-portion 14 and a cover section 15, these parts being relatively rotatable, and means hereinafter described for releasably locking the cover section 15, against removal, on the body-section 14. By preference, the body-section 14 is formed of a circular bottom-plate portion 16 and an annular member, or band, 17 connected with the plate-portion 16 in any suitable manner. The annular member, or band, 17 contains a coin-slot 18 and is provided at its upper edge with an inwardly-projecting continuous flange 19 preferably having a depending lip 20 along its extreme inner edge, the flange 19 containing at intervals there-in a series of recesses 21 to 26 inclusive, these recesses in the particular construction illustrated, being non-uniformly spaced apart.

The cover section 15 is, in the particular construction illustrated, formed of two sheet-metal disks 27 and 28, connected together in any suitable manner. The cover 15 is provided on its under side with depending outwardly-projecting angular lugs 29 to 34 inclusive, preferably stamped from the disk 27 and arranged in a circular series, as represented in Fig. 2, these lugs being so disposed on the cover section 15 that when the latter is applied to body-portion 14 of the bank, to a certain position thereon, these lugs 29 to 34 inclusive will register with the recesses 21 to 26 inclusive, respectively, passing downwardly therethrough and extending below the plane of the lower edge of the lip 19 in which position the disk 27 rests at its under surface upon the upper surface of the flange 19, at which flatwise-abutting surfaces the cover 15 and body-section 14 are relatively rotatable on each other to cause 110

the lugs above referred to, to interlock with the flange 19, it being understood from the drawings that this is possible because the bases of the angular lugs 29 to 34 inclusive, 5 lie within a circle of slightly less diameter than the diameter of the opening presented by the inner edge of the continuous flange 19.

It will be understood from the foregoing 10 that it is necessary, before the cover 15 can be removed from the body-section 14 to open the bank, that the cover occupy such a position on the body-section that these lugs 29 to 34 inclusive, register with the recesses 21 to 26 inclusive, respectively, and to prevent the movement of the cover to a position in which the lugs are in such position of registration, excepting by one using the proper tool, the following described mechanism is 15 provided.

Extending lengthwise of the slot 18 and located at the inner side thereof, is a member 35 of springy material, preferably spring wire located within a housing containing a 25 coin-slot 36 and formed of the side wall 17 and a member 37 extending concentric therewith, at its inner side in spaced relation thereto at opposite sides of the slot 36, and secured in place in any desirable manner. Between its ends at opposite sides of the coin-slot, the wire 35 is deflected downwardly, as represented at 38, and then upwardly and outwardly to present the two 30 portions 39 which, in the normal position of the structure, extend into registration with slots 40 in the member 37, the extremities of the member 35 being deflected upwardly, as represented at 41 and registering with openings 42 in the flange 19, these portions 41 35 extending upwardly through these openings (Fig. 7) in the normal condition of the structure.

In this particular construction, the member 35 also forms a portion of a coin-guard, 45 the central portion of this member being deflected upwardly to extend part-way across the coin slot 18, as represented at 43. The other portion of the coin-guard is formed of a spring member represented at 50 44 which is confined in the above-referred-to housing and co-operates with the member 35, as shown.

The cover 15 contains in its section 27, a pair of openings 45 spaced apart a distance 55 equal to the distance between the sections 41 of the member 35 and in such position that when the parts of the bank are assembled, these openings will register with the sections 41, in which position these sections 60 extend upwardly through the openings 45 and co-operate with the shoulders presented by the walls of these openings.

To assemble the cover and body of the bank, the cover is applied to the body in 65 such position that its lugs 29 to 34 inclu-

sive, register with the recesses 21 to 26 inclusive. The operator then rotates the cover on the body, pressing these parts together sufficiently against the resistance of the member 35, to move the extremities of the 70 lugs 29 to 34 inclusive beneath the flange 19, to a position in which the openings 45 register with the locking sections 41, which latter immediately spring outwardly into the openings 45 and lock the cover and body 75 section against rotation, in which position of the parts the lugs 29 to 34 are out of registration with the recesses 21 to 26.

Any suitable tool may be used for operating the locking sections 41 to withdraw 80 them from the openings 45. Such a tool is represented in Fig. 4 and comprises a pair of legs 46 pivotally connected together at 47 and provided at their outer ends with outwardly-turned flanges 48 having projections 49. To withdraw the locking sections 41 from the openings 45, the operator inserts the legs 46 of the tool into the interior of the bank through the slots 18 and 36 to position the portions 49 thereof in the 90 slots 40 above the sections 39, and then by tilting the tool in the slots, depresses the sections 39.

In the construction illustrated in Figs. 8 to 13 inclusive, the general features of 95 the bank are substantially the same as those of the other construction, as above described, but instead of the locking mechanism and the particular lug construction of the cover shown in Figs. 1 to 7 inclusive, the following described mechanism is provided.

According to the illustration in Fig. 10, the cover 15 is equipped with lugs 29^a, 30^a, 31^a, 32^a, 33^a, and 34^a, which are non-equally spaced apart and are adapted to register 105 with the recesses 21^a to 26^a inclusive, respectively, when the cover is applied to the body of the bank, these lugs being formed by partially severing portions of the metal of the cover and offsetting them from the 110 plane of the disk.

Extending across that portion of the inner surface of that portion of the wall 17, which contains the coin-slot 18, but preferably spaced therefrom, is a plate 50 of spring 115 metal which contains a slot 51 registering with the coin-slot 18, and is rigidly held between the flange 19 and the bottom of the body-section 14 by means of a lug 52 struck up from a portion of the bottom of the body-section 14, and a lug 53 provided on the upper edge of the member 50 and extending into a slot 54 in the flange 19. The ends of the plate 50 are deflected outwardly to form flanges 55, which bear against the inner face of the wall 17, and the portions of the metal of this member at the ends of the slot 51 are deflected inwardly, as represented at 125 56. Located between the wall 17 and the member 50 is a coin-check formed of two 130

similar members 57 made of spring-wire, preferably of the shape shown to afford the pairs of opposed spring sections 58, which preferably extend normally into engagement with each other, as shown, and lie in a plane medial of the slot 18 as shown, these members permitting coins to be forced between them and into the bank, but preventing removal of the coins from the bank through the slot 18. The member 50 is provided adjacent its ends with projections 59 which extend upwardly through slots 60 in the flange 19, these slots being of such form, as shown, as to permit of the flexing of the ends of the member 50 in a direction for moving the projections 59 inwardly, or, in other words, in a direction toward the center of the bank from the normal position represented in Figs. 9 and 11. The projections 59, which form locking-lugs, coöperate with shoulders 61 afforded by recessed portions 62 in the cover 15, preferably in the disk 27. The recessed portions 62 are formed of the recessed portion 63 of a dimension corresponding with the recess 60 and a recessed portion 64 which is of substantially the same dimensions as the recessed portion 63 and opens into a contracted, recessed, portion 65, which in turn opens in to the recessed portion 63 which forms the shoulder 61 at one side of the contracted, recessed, portion 65 and a shoulder 66 at the opposite side thereof, the openings between the recessed portions 63 and 65 and represented at 67, being relatively contracted and preferably of a width slightly in excess of the thickness of the locking-lugs 59 with which they coöperate. The position of the recessed portions just described is such, relative to the lugs 29^a to 34^a inclusive, that when the cover 15 is applied to the body 14 to a position in which the lugs last referred to register with the recesses 21^a to 26^a inclusive, the locking-lugs 59 extend into the recessed portions 64 which register with the recesses 60 in the flange 19, and upon rotating the cover 15 in anticlockwise direction in Fig. 9 on the body-section 14 to move the lugs 29^a to 34^a inclusive out of registration with the recesses in the flange 19 with which they coöperate, for inter-locking these lugs with the flange 19, the outermost inclined walls of the recessed portions 65 ride against the locking lugs 59, forcing them toward the center of the bank in order that they may extend into the contracted portions 67, whereupon continuing the rotation of the cover, the lugs 59 register with the recessed portions 63 and spring outwardly to the position illustrated in Fig. 9 in which they lie between the shoulders 61 and the opposite end wall of the recessed portion 63.

It will be understood from the foregoing that the cover 15 is thus locked against rotation on the body 14 of the bank, and the lugs 29^a to 34^a, inclusive, cannot be moved into registration with the respective recesses 21^a to 26^a inclusive, until the locking lugs 59 are moved inwardly to a position in which they register with the restricted portions 67 of the recesses, (Fig. 12). A suitable tool is provided for flexing the ends of the member 50 to move the lugs 59 to the position stated, to permit rotation of the cover 15 to the proper position for effecting its separation from the body. A tool for this purpose is represented in Fig. 12 and comprises a pair of legs 68 pivotally connected together at 68^a and provided at their outer ends with outwardly-turned extensions 69 presenting cam surfaces 70 and shoulders 71. To shift the lugs 59 into registration with the portions 67 of the recesses, the operator inserts the extremities of the portions 69 of the tool, between the ends of the slot 18 and the adjacent pairs of spring-sections 59. The operator by grasping the opposite ends of the legs 68 and drawing them together, spreads the ends thereof which are disposed at the inside of the wall 17, and causes them to ride at their cam surfaces 70 against the portions of the metal of the member 50 at the ends of the slot 18, thus by the camming action produced, flexing the ends of the member 50 in an inward direction and consequently the locking lugs 59 carried thereby. The shoulders 71 are provided for coöperation with the ends of the coin-slot 18 and the parts are so proportioned that when the tool is operated as set, to a position in which these shoulders 71 engage the ends of the coin-slot 18 and thereby limit the operation of the tool, the lugs 59 will be in registration with the contracted portions 67 of the recesses, (Fig. 12).

It will be manifest from the foregoing description that the cover 15 may be locked to the body 14 of the bank by the mere act of applying the cover thereto in the proper position, as stated, and thereupon rotating it as described.

I do not wish to be understood as intending to limit my invention by the particular showing presented, it being my intention to claim my invention as fully and completely as the prior state of the art will permit.

What I claim as new and desire to secure by Letters Patent is—

1. In a bank structure, the combination of a body member carrying an inwardly-projecting flange spaced from its bottom and containing a recess, a cover section rotatable on said body member and carrying a lug adapted to enter said recess upon applying the cover to said body member and to interlock with said flange when said cover is rotated on said body member out of assembling position, and locking means for releasably locking said cover section against return to a position on said body

120
125
130

- member in which said lug disengages from said flange, said means comprising a shiftable member on said body member operating through an opening in said flange, and a shoulder on said cover located on a part thereof other than said lug and with which said shiftable member engages.
- 5 2. In a bank structure, the combination of a body member carrying an inwardly-projecting flange spaced from its bottom and containing a recess, a cover section rotatable on said body member and carrying a lug adapted to enter said recess upon applying the cover to said body member and to interlock with said flange when said cover is rotated on said body member out of assembling position, and automatically operating locking means for releasably locking said cover section against return to a position on
- 10 said body member in which said lug disengages from said flange, said means comprising a shiftable member on said body member operating through an opening in said flange, and a shoulder on said cover section located on a part thereof other than said lug and with which said shiftable member automatically engages upon the act of rotating the cover to a position in which said lug interlocks with said flange.
- 15 3. In a bank structure, the combination of relatively rotatable receptacle-forming sections, one of which contains a coin-slot, and locking means for releasably locking said sections against separation comprising
- 20 a plate on the said section containing said
- 25
- 30
- 35

coin-slot, said plate containing a coin-slot in registration with said first-referred-to coin-slot, means securing said plate at its upper and lower edges between its ends to said last-referred-to section, the ends of said plate being flexible and forming flexible locking members, and surfaces on the other of said sections with which said locking means interlock.

4. In a bank structure, the combination 45 of relatively rotatable receptacle-forming sections, one of which contains a coin-slot and carries an inwardly-projecting flange spaced from the bottom of said section and containing a recess and the other of which 50 carries a lug adapted to enter said recess upon assembling said sections and interlock with said flange when the sections are relatively rotated out of assembling position, and locking means for releasably locking 55 said sections against separation comprising a plate on said section containing said coin-slot, located between the bottom of said section and said flange and containing a coin-slot registering with said first-referred-to 60 coin-slot, said plate carrying a lug between its ends which extends into a slot in said flange for securing the plate in position, the ends of said plate being flexible and forming flexible locking members which operate 65 through openings in said flange, and surfaces on the section carrying said first-referred-to lug with which said locking means interlock.

JOSEPH KOMOROUS.
